PILOT REGULATOR ATTACHMENT

Ralph C. Hughes, Anderson, Ind., assignor to
 Reynolds Gas Regulator Co., Anderson, Ind., a
 corporation of Indiana

Application February 19, 1932, Serial No. 593,999

3 Claims. (Cl. 50—23)

My invention relates to pilot regulator attachments constructed for detachable mounting beneath a main casting of pressure regulator structures and particularly for pressure regulators for maintaining a uniform pressure in gas service pipes desired to supply fuel gas to furnaces having suitable pilot light control, irrespective of the fluctuation of pressure in the supply mains for such furnaces, or for other gaseous burners which are suitably installed in other casings rather than a furnace. Such pressure regulators will preferably include a valve member in the intermediate main casting normally urged downward to open position, and will have a diaphragm casing 15 mounted upon and above said casting and connecting means for operating the valve.

It is an object of my invention to provide in the upper casing a plate attached to the lower surface of the diaphragm, the plate having a reduced lower end movable through an aperture in the lower section of said diaphragm casing and axially connected with a valve stem for actuating the valve in the main casing.

It is a further object of my invention to provide beneath said main casting a pilot control attachment device having means for detachable connection with the main casting at a bottom opening in the latter, including as a unitary part of the same, a diaphragm casing having upper and lower chambers with an intermediate diaphragm having its peripheral edge clamped between flanges of the casing sections, such upper chamber responsive to pressure in the outlet chamber of the main casting, and also having a fitting for detachable connection with a pipe leading to a pilot light for supplying the main gas burner, as will be understood.

A further object of my invention is to provide said diaphragm casing for the pipe fitting as one whose upper section is externally threaded and cylindrical in form for attachment to a threaded orifice in the lower wall of the main casting, and on the outlet side of the main valve, so that connection of said pipe fitting with a pipe leading to a pilot light of a furnace or other gases to be heated supplied with gas fuel from said casting, will be controlled by the fluid pressure in the outlet side of said main casting.

It is a further object of my invention to provide such a detachable lower diaphragm casing with a threaded thimble integral with the upper section of said lower casing to take the place of the usual plug ordinarily seated in a lower opening in the lower casting section, such upper casing section having pipe connection with a

pilot light of a furnace or other heater ordinarily supplied with gas fuel from the main valve casting.

Other objects and advantages of my invention will hereinafter appear in the following description and the novel details particularly pointed out in the appended claims.

In the accompanying drawing, the figure illustrates a vertical sectional view of a gas regulator with the upper and lower diaphragm attachments connected with the main casing and embodying my invention, the section being taken in the plane of the axes of the inlet and outlet connections.

Referring now to the drawing, the valve mechanism requires a valve casting 5 having an inlet chamber 6, an outlet chamber 7, and a pressure chamber 8 in the upper casting 13. In the partition wall 9 is a valve regulated opening 10 in which I provide a valve 11, the latter being mounted on a vertical stem 12 extending upwardly into the upper diaphragm casing 13. Upon the casting 5 the casing 13 rests, there being a diaphragm 14 clamped at its peripheral edges between the casting 5 and the casing 13 as shown at 15. The valve member 11 is frusto-conical and will close against the valve seat 37 on the thimble 38 provided in the vertical opening 10.

A reduced upper end of stem 12 is externally threaded at 16 to receive adjustably thereon the clamping block 17 having an internally threaded central aperture for engaging the reduced end of the stem. A washer 18 rests on the shoulder 19 of the stem 12 to clamp the diaphragm against the block 17 which has its upper surface expanded as a plate 20 applied beneath the casing diaphragm 21 centrally apertured.

A threaded opening 22 is provided in the bottom of the casting 5 which has ordinarily been of service for insertion of certain tools for repairs and adjustment, and usually closed by a plug. In my improved attachment for controlling a pilot light, diaphragm casing 23 is detachably suspended from the main casting by providing the upper section 40 of such casing with an upwardly-projecting threaded sleeve 24 which is securely inserted in said opening 22, there being a port aperture 25 in the section wall, axial of said sleeves, which serves the purpose of providing a valve seat 26 against which a valve member 27 may be urged for closing position, and thereby cut off communication between the outlet chamber 7 and the diaphragm chamber 28 of the case 23.

The diaphragm 21 of the upper casting is

clamped between the plate 20 and the upper metallic plate 29 by a screw 30, inserted through the diaphragm, and into the upper end of the threaded socket 66 in the block 17. The main valve 11 is normally urged downwardly to open position by gravity and such tendency is supplemented by coil spring 31 interposed between the head of the screw 30 above the plate 29, and the extension 32 of an adjusting screw applied to the upper end of the coil. The upper section 39 of the upper casing 13 is provided with an integral upwardly extending sleeve 33 internally threaded to receive adjustably therein the screw 34. The section 39 is also provided with a vent 35 and a protecting cover 36 having ear lock provision with the case.

The upper section of the detachable casing for the pilot light is designated by the numeral 40 and is provided with an upwardly extending threaded sleeve 41 for detachable insertion in the opening 22 of the casting, and is further provided with a threaded opening 42 for receiving therein an externally threaded fitting 43 for detachable connection with a pipe 44 leading to a pilot light for the main burner for which the outlet connection 45 of the main casting 5 supplies the gaseous fuel.

The lower section 46 of the attachment case 23 has peripheral flange connection with the section 48, clamping between them the peripheral edge of the diaphragm 47 which is centrally apertured to receive therethrough the reduced threaded end 48 of the lower end of the valve stem 49 upon which the valve member 27 is mounted. A washer 50 is mounted on said reduced end and is positioned against the shoulder 51, the diaphragm 47 being clamped between the washer 50 and the lower plate 52 also apertured to receive the screw threaded end of the stem, and a lock nut 53 clamps the parts together.

The lower section 46 of the attachment casing 23 is provided with a socketed and integral downwardly projecting portion 54 which has a central aperture threaded to receive an adjusting screw 55 with a lock nut 56. A coil spring 57 has its lower end seated in the socket 58 and properly positioned upon the ends of the screws 48 and 55, and will normally be adjusted to support the valve 27 in open position. A further normal support of the diaphragm 47 by pressure exerted on its lower surface is also present in the lower chamber of such casing, as will be evident. The sections of casing 23 will be detachably clamped together by bolts 59. It is to be noted that the valve member 27 is positioned oppositely relative to its seat, to valve member 11, but that since the two springs 31 and 57 are oppositely directed, their tendency will be to normally open both valves, so that fluid entering the chamber 6 will normally pass through the port 10 into the outlet chamber 7 and thence through the outlet 45 and through the pipe 44 to the pilot light.

A small aperture 63 is also provided in the partition wall 9 to permit sufficient gas to pass through into the outlet chamber for operation of the pilot regulator, so that the pilot light can always be maintained, even if the main valve 11 should close tightly.

The normal pressure of the spring 31 tending to open the valve 11, is opposed by the fluid pressure in the lower chamber 8 of the diaphragm casing 13, which pressure reaches this chamber through the reduced channel 60 of the vertical aperture 61 leading upward from the main out-

let chamber 7 in the casting 5, so that variation in the demand in the outlet main will correspondingly vary the pressure in the chamber 8.

In operation, the gas passes into the inlet chamber 6 and out through the valve 11 into the outlet chamber 7 and the connection 45 to the point of demand which may be assumed to be a furnace burner. A portion of the gas in the outlet chamber 7 will, when my pilot attachment 23 is used, pass downwardly through the port 25 into the upper chamber 28 of the attachment, a small aperture 62 leading from 28 to the opening 42 and reach the pipe 44, since the valve member 27 is normally in its raised position.

Whenever the pressure on the delivery side of the main valve builds up for any reason, a back pressure will be created which, passing through the opening 60 and 61 into the chamber 8, will tend to raise the diaphragm 21 and move the main valve 11 toward closed position, thereby shutting off flow of gas through the valve until the pressure on the delivery side drops, which will permit relief of pressure from the diaphragm chamber thereby again permitting the valve to move to open position by its normal bias. Such variation in pressure in the outlet chamber 7 will also control the valve 27 by varying pressure in the chamber 28 attachment 23, which pressure will also and correspondingly vary with the yielding pressure in the lower chamber of such attachment.

It is the purpose of my improved mechanism to normally open both valves by the pressure of the coils in the main casting and the attached casing, and so supply the main burner, if such receives the gas from the outlet chamber; and to automatically tend to close the valve 11 when the demand decreases. The pilot light will however, be supplied from the chamber 28 whether the main demand is lessened or increased, since the valve 27 will not be positively closed against the force of the spring 57, since excessive pressure in chambers 7 and 28 automatically operates valve 27 correspondingly, but permits entrance of gas for the pilot when the main burner is shut off, and will automatically control pressure in the line 44, even when the valve 11 is held abnormally low in its orifice, as by the presence of some particles of matter in the port preventing proper closing action of the valve.

It is a special advantage of my attachment 23 that it is so readily removable by merely unscrewing the sleeve 41 from the opening 22, after the connection 43 has been detached. The opening 22 may be closed with the ordinary threaded plug when the main regulator casing is to be used, for any purpose, without the control attachment for a pilot. It is also evident that other forms of main valve pressure regulators having a threaded opening in their bottom wall, may be fitted with my attachment, when a pilot light is to be supplied. The attachment 23 may be connected by the threaded sleeve 41 in a corresponding opening 22 of regulators for operating the main valve under varying conditions of pressure supply and demand, by adjustment of the plug 55.

Having fully described my invention, what I now claim as new and desire to secure by Letters Patent is:

1. A combined line pressure and pilot pressure regulator valve comprising a casing having a main inlet chamber, a main outlet chamber, a main diaphragm chamber and a pilot diaphragm chamber, a wall between the main inlet chamber and the main outlet chamber, said wall hav-

ing an opening therein, a diaphragm in the main diaphragm chamber, a valve carried by said diaphragm to close the opening in the wall between said outlet and inlet chambers, resilient means 5 acting to maintain said valve in an open position, a passageway between the outlet chamber and said diaphragm chamber whereby a predetermined pressure in the outlet chamber will close said valve, a second diaphragm in the pilot diaphragm chamber, a passageway between said pilot diaphragm chamber and said outlet chamber, a pilot valve carried by said second named diaphragm and arranged to close said passageway, resilient means acting to maintain said last 10 named valve open until a predetermined pressure exists in said pilot valve diaphragm chamber, and an independent low pressure opening communicating with said pilot diaphragm chamber.

10 2. The combination with a pressure regulator comprising a valve casing having a high pressure inlet, a low pressure outlet and means disposed therebetween and responsive to variations in the pressure at the low pressure outlet to control the 15 pressure at the low pressure outlet, of a second low pressure outlet a passageway in said casing in communication with both of said low pressure outlets, a valve arranged to close or open said passageway, resilient means acting to normally maintain said valve open and means

responsive to the variations of pressure at the second named low pressure outlet to control the position of the second named valve, whereby two independent low pressure lines having different pressures may be simultaneously maintained. 5

3. A pressure regulator including a valve casing having opposite high pressure inlet and low pressure outlet openings and an internally threaded bottom opening, a valve member disposed therebetween and means responsive to the 10 pressure of the outlet opening to operate said valve to control the flow between the inlet and outlet openings and thereby maintain a predetermined low pressure at the outlet opening, a pilot regulator having an integral upwardly 15 threaded sleeve for detachable connection with the threaded opening in said bottom wall, said pilot regulator having a chamber therein, a passageway between said chamber and said low pressure outlet, a diaphragm in said chamber having a low pressure outlet, a valve carried by said diaphragm and adapted to control the flow between the low pressure outlet and said chamber, resilient means acting to maintain said valve open, whereby the flow between the first named 20 low pressure outlet and the second named low pressure outlet is controlled by variations in pressure at the second named low pressure outlet. 25
